[57] CLAIM

The ornamental design for vent control panel for a produce storage container, as shown and described.

DESCRIPTION

FIG. 1 is a top, side and front perspective view of vent control panel for a produce storage container showing the new design;

FIG. 2 is a front elevation view thereof, the ornamental features of the vent controls not being visible from the rear; FIG. 3 is a left side elevation view thereof, the right side elevation being a mirror thereof; and, FIG. 4 is a bottom plan view thereof.

The broken line showing the container periphery is of illustrative purposes only, and forms no part of the claimed design.
